US00D727290S

(12) **United States Design Patent**
Kim et al.

(10) **Patent No.:** US D727,290 S
(45) **Date of Patent:** ** Apr. 21, 2015

(54) **SPEAKER**

- (71) Applicant: **LG Hausys, Ltd.**, Seoul (KR)
- (72) Inventors: **Tae-Woo Kim**, Yongin-si (KR); **Keun-Tae Kim**, Seoul (KR); **Han-Sung Choi**, Seoul (KR)
- (73) Assignee: **LG Hausys, Ltd.**, Seoul (KR)
- (**) Term: **14 Years**
- (21) Appl. No.: **29/454,689**
- (22) Filed: **May 13, 2013**

(30) **Foreign Application Priority Data**

Mar. 14, 2013 (KR) 30-2013-0012919

- (51) **LOC (10) Cl.** **14-03**
- (52) **U.S. Cl.**
USPC **D14/208; D14/209.1**
- (58) **Field of Classification Search**
USPC D14/167, 168, 170-172, 188, 194-196, D14/204, 207, 209.1, 210-216, 219, 221, D14/222, 224, 496; 181/143, 144, 147, 148, 181/150, 153, 157, 198, 199; 381/300-303, 381/306, 332, 333, 336, 345, 361-364, 381/386-388; 369/6-12
